RAZOR

Jack M. Stein, Los Angeles, Calif., assignor to Reelshav Corporation, Los Angeles, Calif., a corporation of California

Application September 15, 1950, Serial No. 12,200

Term of patent 14 years

(Cl. D22—3.1)

To all whom it may concern:

Be it known that I, Jack M. Stein, a citizen of the United States of America, residing at Los Angeles, in the county of Los Angeles and State of California, have invented a new, original, and ornamental Design for a Razor, of which the following is a specification, reference being had to the accompanying drawings, forming a part thereof:

The dominant features of the design reside in the portions shown in full lines.

I claim:

The ornamental design for a razor, substantially as shown and described.

JACK M. STEIN.
